C. HILSCHER

THREAD GUIDING DEVICE FOR COTTON KNITTING MACHINES

Filed Aug. 26, 1921

Patented Sept. 2, 1924.

1,507,482

UNITED STATES PATENT OFFICE.

CURT HILSCHER, OF CHEMNITZ, GERMANY.

THREAD-GUIDING DEVICE FOR COTTON KNITTING MACHINES.

Application filed August 26, 1921. Serial No. 495,811.

To all whom it may concern:

Be it known that I, CURT HILSCHER, a citizen of the German Republic, residing at Chemnitz, Germany, have invented certain new and useful Improvements in a Thread-Guiding Device for Cotton Knitting Machines, of which the following is a specification.

This invention has for its object to bring automatically into the required working position, when stockings are to be produced upon the Cotton knitting machine, that thread guiding device which is required for the knitting of the rows of loops between the heel parts and to limit their course at the knitting of these rows in both working directions. The invention has for its object to do away with the manual labour which had to be done hitherto for this special kind of work so that it is no longer necessary to stop the machine whereby the efficiency is increased considerably.

In order that the invention may be clearly understood I shall proceed to describe the same with reference to the accompanying drawing, wherein:—

Figs. 1 and 2 are front elevations of the thread guiding device.

Fig. 3 is a plan view of the same and

Fig. 4 is a side elevation.

Fig. 5 illustrates diagrammatically the part of the stocking which has to be provided with the rows mentioned.

The intermediate rows *c* (Fig. 5) are to be knitted at the beginning of the knitting of the heel parts *b* when the leg of the stocking has been knit already and these rows serve to facilitate the subsequent running on of this part upon the needles when the foot of the stocking has to be knit. The thread-guide rail 6, designed for the knitting of these rows of loops carries one thread guide *e* for each row of needles (set). This thread-guide rail adopts, before it is operated, the position shown on Fig. 1 in which the thread guide *e* is situated at the end of its greatest course. The adjustment and operation of this rail has to be effected in such a manner that the thread guide *e* travels between the heel parts *b* (Fig. 5) in order to produce the rows *c*. With this object in view the well known counting device of the Cotton knitting machine (not shown on the drawing) shifts first, when the last row of loops *d* of the leg is worked from left to right, the well known slide *k* with

driver *l* of the so-called change-head *m*, with the aid of a rod *f* (Fig. 4) and lever *g*, *h* with connecting member *i*, so that the driver which stands over the thread guide rail 5 gets over the thread guide rail 6 and engages with the fork of the same which is formed by the angle iron *n*. The next following odd row produced at the sinking of the loops in opposite direction for adjusting the thread guide for the knitting of the loop parts *b* (Fig. 5) is utilized to bring the thread guide *e* into the position required for the working of the rows *c*, as the driver *l* draws the rail 6 along in the direction of the sinking (from right to left) until a stop *r* of said rail has reached the stop *p* in a fixed arm *o* (Fig. 2). The travel in the left hand direction is thus limited. A stop *q* of the thread-guide rail 6 serves for limiting the travel in the right hand direction, said stop having previously, during the movement of thread guide rail 6 in the left hand side direction, the spring controlled stop *p*, which, immediately after having been released by stop *q* is lowered again by the action of its spring so that this stop is now situated between the two fixed stops *q* and *r* whose mutual distance corresponds to the width of the rows *c* (Fig. 5) which have to be worked now simultaneously with the heel parts *b*. After the rows *c* have been knitted the thread guide rail 6 is thrown out of gear simply by the return of the slide *k* and of its driver *l* over the thread guide rail 5 caused by the above mentioned counting device. The rail 6 will thus be stopped when the knitting of the heel parts *b* is being continued and the thread guide *e* will no longer feed the thread to the needles, the part *c* of the fabric being detached from the needles. After the heel parts have been finished, the thread guide rail 6 is released by hand to the initial position in similar manner as with the rails carrying the guides for the heel threads.

The stop *o p* serves for both stops *q* and *r* as an abutment. As it is however originally not situated between these stops *q* *r* but in the position shown in Fig. 1, the stop *p* must be put out of operation when the stop *q* passes below the same. For this reason the stop *p* is movably arranged on the arm *o* so that it can be raised by the stop *q*.

I claim:—

1. An improved thread-guiding device for Cotton knitting machines for the produc-

- tion of stockings with two heel parts comprising in combination thread guide rails for the knitting of the leg, an auxiliary thread guide rail for the knitting of the 5 rows of loops between the heel parts, stops for the ends of the auxiliary rail, stops fixed on said rail for determining the length of travel of said rail and a stop on the machine within the range of travel of said 10 rail, said stops on the auxiliary rail working together with said stop of the machine for determining the working travel of said auxiliary thread guide rail.
2. An improved thread-guiding device for 15 Cotton knitting machines for the production of stockings with two heel parts comprising in combination with the thread guide rails for the knitting of the legs, an auxiliary thread guide rail for the knitting of the 20 rows of loops between the heel parts, stops for the ends of said thread guide rails, a stop fixed upon said auxiliary rail and hav-
- ing a surface inclined in one direction of travel, a second stop fixed on said auxiliary rail at a distance apart from said first mentioned stop which corresponds with the length of travel required for the working of said rows of loops between the heel parts, an arm projecting from the machine frame, a stop movably mounted in said arm adapted 25 to be raised by said stop with the inclined surface when said rail is moving into the working position and a spring for controlling said movable stop so that it descends at once after having been raised to serve as 30 an abutment for the second mentioned stop of the auxiliary rail.
- In testimony, that I claim the foregoing as my invention, I have signed my name in presence of two subscribing witnesses.

CURT HILSCHER.
